AUTOMATIC NECKTIE RACK, OR SIMILAR ARTICLE

Melvin A. Goldfeder, Rockville Center, N.Y., assignor
to Swank, Inc., Attleboro, Mass.

Filed Sept. 14, 1972, Ser. No. 288,925

Term of patent 14 years

Int. Cl. D8—08

U.S. CL. D6—117

FIG. 1 is a top plan view of the automatic necktie rack, or similar article, embodying the design of my invention;

FIG. 2 is a front elevational view thereof;

FIG. 3 is a rear elevational view thereof; and

FIG. 4 is an end elevational view thereof.

I claim:

The ornamental design for an automatic necktie rack, or similar article, as shown.
